United States Patent Office.

H. K. HAZLETT, OF ST. LOUIS, MISSOURI.

Letters Patent No. 100,144, dated February 22, 1870.

FEED-WATER PURIFIER FOR STEAM-GENERATORS.

The Schedule referred to in these Letters Patent and making part of the same.

To all whom it may concern:

Be it known that I, H. K. HAZLETT, of the city and county of St. Louis, State of Missouri, have invented a new and useful improved Feed-Water Purifier for Steam-Generators, of which the following is a full, clear, and exact description, reference being had to the annexed drawing making a part of this specification and representing a side elevation of same, with a portion in section.

Its object is to purify the feed-water in its passage from the heater to the boilers, so as to prevent incrustation and save the labor of frequent cleaning of the latter.

It consists of a tank, A, having an inner tank or lining, B, extending from the top nearly to the bottom, and leaving a space between itself and the sides of A. A pipe, a, passes from this lining through the side of the tank, while two other pipes, b c, lead from A, the one at the bottom and the other at the side, as seen.

Baskets D and E, having wire bottoms, and attached to a cover, H, are made to fit inside of B, the lower basket extending a little below the bottom of B. The cover and the baskets are represented as raised out of the tank. The cover is made to fit tightly, and is secured by nuts and bolts, or any other suitable device which will permit its being removed easily and quickly. The lower basket may be filled with oak bark, and the other with hay or other suitable filtering substance, such as commonly used.

The pipe a is connected with the heater, and to c is attached the hot-water pump, each, as well as b, being furnished with suitable cocks, not shown.

The hot water entering a falls into E, and thence through D passes into the tank A, the sediment not taken up by the baskets naturally falling to the bottom, while the purer water rises and occupies the space between A and B, whence, by the pipe c, the pumps force it into the boilers, c being placed some distance above the bottom of A.

About once in twenty-four hours the cock in b may be opened, and the water allowed to carry the deposit away from the bottom of the tank, which is made concave to facilitate this operation. As it will not require much water for this purpose, the hot-water pump may be kept in operation all the time, so the operation will cause no delay.

When the baskets get "foul," they may be removed

by attaching a "tackle" to the ring k, and while they are being cleaned another set may be inserted, it being best to have a spare set, so that no time may be lost, and the supply of hot water be uninterrupted.

The tank may be placed wherever most convenient, and may be supplied with feet, o o o", the latter not shown, by which it may be bolted to the deck.

If desired, the baskets need not be united, but may be separated, which, in a large apparatus, will probably be more convenient in removing them from the tank.

The number of baskets also may be increased, and the filtering substance placed in them varied, but those I have mentioned I find to work very well in practice, and for a small apparatus two baskets answer every need.

To give some idea of the dimensions of the apparatus, I will describe one now in actual use. It is forty inches in height and the same in width. The space between the tanks is eight inches, and the inner tank extends within eight inches of the bottom of the outer tank. It is made of No. 10 iron, and amply supplies a pair of boilers each thirty-six by twenty feet. I of course do not limit myself to any of these dimensions, since they may be varied at pleasure, as circumstances may require.

With this apparatus purer water is supplied the boilers, thereby very materially diminishing their wear. No time is lost in frequent cleanings, which, on the western waters particularly, is a matter of great annoyance; and as the "blowing off" does not interrupt the supply of hot water, or necessitate the cooling of the boilers, the extra fuel required in "firing up" is saved.

I am well aware that attempts have heretofore been made to purify feed-water by passing it over and through plates arranged in a tank, which is kept hot; but I make no claim to any novelty in the principle displayed, but merely claim as my invention, and desire to secure by Letters Patent—

The tanks A B, baskets D E, and pipes a b c, when constructed, arranged, and operating substantially as and for the purpose shown and specified.

H. K. HAZLETT.
